PACKAGING MACHINE

Earle C. Sherman, Monroe, La., assignor to Olinkraft, Inc.

Filed Feb. 11, 1972, Ser. No. 225,696

Term of patent 14 years

Int. Cl. D15—99

U.S. Cl. D55—1 C

FIG. 1

FIG. 2

FIG. 3

FIG. 4

FIG. 5

FIG. 1 is a top view of the packaging machine showing my new design;

FIG. 2 is a side view of the packaging machine shown in FIG. 1 and taken along lines 2—2 of FIG. 1;

FIG. 3 is a bottom view of the packaging machine shown in FIG. 1;

FIG. 4 is an end view of the packaging machine taken along lines 4—4 of FIG. 3; and

FIG. 5 is an end view of the packaging machine taken along line 5—5 of FIG. 3.

A side view taken along line 6—6 of FIG. 1 is not shown but has substantially the same appearance as the side view shown in FIG. 2.

I claim:

The ornamental design for the packaging machine, substantially as shown and described.
